RADIOCIRCUIT

Application filed March 18, 1926. Serial No. 95,709.

Our invention relates to new and useful improvements in the art of radio frequency amplification, and it particularly relates to a method of overcoming variations of efficiency of amplification for different frequencies commonly encountered in circuits employed in the reception and amplification of radio signals.

It is well known that in radio frequency amplifying systems the amplification of the system is affected by the feedbacks occurring through the electro-magnetic coupling from the plate circuit and other successive inductive circuits and through the capacity between grid and plate back into the tuned grid circuit. If this feedback energy increases the total amount of energy sufficiently to overcome the losses in the circuit, oscillation will occur. The effect of these feedbacks can be overcome by absorbing an amount of energy which is equal to the increase in energy supplied by the feedbacks to the tuned circuit. The effect of these feedbacks is commonly spoken of as "reducing the effective resistance of the tuned circuit." If an extra resistance be placed in the tuned circuit such that the I^2R loss in it is equal to the I^2R gain from the feedbacks, the effects of the feedbacks will be cancelled out. This feedback energy is a function of frequency and consequently the energy dissipation of the compensating resistance should also be a function of frequency.

The common methods of reducing these feedbacks are the use of a potentiometer in connection with the grid circuit or a resistance of high value in some part of the radio frequency circuit. These methods introduce a loss which is large enough to control the greatest feedback at any frequency for which the system is used. Consequently for all other frequencies, a loss is introduced which more than compensates for the feedback. Another system is the well-known "neutro-dyne" system which can neutralize only electro-static feedback.

An object of this invention is to provide an automatic method for absorbing the feedback energy, both electro-magnetic and electro-static, which will absorb just enough energy

at each frequency to cancel out completely, the effect of the feedback or modify the effect in any desired manner.

One of the objects of our invention is to accomplish the above desired result without appreciably affecting the normal tuning characteristics of the system. It is also important that the proposed compensating network need not be interposed directly in the resonant circuit.

An additional object of our invention is to provide a network that may be used in a great number of circuit relations to effectively oppose the variations with frequency, in the efficiency of amplification without reducing the sensitivity of the system.

Another object of our invention is to provide a network that will have an inherent frequency loss characteristic in its association with the circuit, and that will require only initial adjustment for any circuit or tube with which it is used.

An additional object of the invention is to provide a compensating network of impedance devices that will not require careful design or adjustment and that are admirably suited to commercial manufacture.

An additional object of the invention is to so modify the characteristics of an amplifying system as to obtain a maximum amplification at all frequencies without permitting the system to oscillate at any frequency, by absorbing just enough energy at each frequency to prevent oscillation.

Another object of this invention is to so modify the amplification at each frequency as to produce any desired frequency gain characteristic in the system, i. e. the relationship between the amplification of the system and the frequency for which the system is tuned.

Figure 1 of the accompanying drawings is a diagrammatic view of a radio frequency amplification system showing a characteristic application of our invention.

Fig. 2 shows characteristic curves that diagrammatically illustrate the relation of the amplification of a radio frequency stage to the turned frequency of the system.

Fig. 3 is a diagrammatic view of a radio

frequency amplification system illustrating the use of an energy absorbing network of the character herein described in coupled relation with the tuned circuit.

5 Fig. 4 is a diagrammatic illustration of a radio frequency system embodying the invention in which a series-parallel network is inserted in the tuned circuit in accordance with the invention.

10 Fig. 5 is a diagrammatic view of a circuit showing one application of a network of the proposed character to the grid circuit of the vacuum tube.

15 Figs. 6, 7, 8 and 9 diagrammatically illustrate other applications of the invention to the plate circuits of radio amplification systems.

The operation of the invention can be illustrated by referring to the specific circuit of Fig. 1. This circuit, to which our invention is applied, is diagrammatically shown. The conventional parts of the circuit are indicated by conventional characters. A signal receiving inductance L_1 is connected in a normal manner to the grid and filament of a vacuum tube. An adjustable tuning condenser C_1 , for tuning the receiving circuit to different signal frequencies, is connected in shunt with the inductance L_1 . A network Z_1 and Z_2 of the character herein proposed is connected across the grid and filament of the vacuum tube as shown. The plate 3 is connected to the remainder of the system which is represented by the conventional symbol L_2 as will be understood by those skilled in the art.

In this circuit, the term L_2 will be used to represent the combined self-inductance of the plate circuit and the mutual inductance of the plate circuit caused by the circuit with which the plate circuit is electrically and magnetically coupled. In accordance with well-known vacuum tube theory, this inductance L_2 causes an in-phase voltage to be fed back through the plate grid capacity, which we will herein conventionally refer to as C_2 , and applied to the grid of the tube. The magnitude of this voltage will depend on the values of L_2 and C_2 , the frequency, and the impedance between the grid and filament of the tube. Further, in accordance with well-known vacuum tube theory, the tube will go into oscillation when the voltage thus fed back through the grid reaches a certain magnitude. In addition to the above mentioned electro-static voltage feedback, an in-phase electro-magnetic feedback may take place from any of the successive coils embodied in L_2 to the tuning circuit, depending upon the geometrical relation of the coils and wiring and the frequency. This form of feedback may also be a cause of or give assistance in setting up objectionable oscillation in the tube circuit.

35. In accordance with our invention, as ap-

plied to the circuit shown in Fig. 1, we propose to connect a network consisting of the resistance Z_1 and the capacity Z_2 between the grid and the filament. The function of the impedances Z_1 and Z_2 is to equalize the amplification of the entire circuit over the desired frequency range. Z_1 being a resistance does not vary with frequency. Z_2 being a condenser, its impedance varies with frequency. Consequently the amount of current through the network Z_1Z_2 varies as the frequency is varied, and therefore the energy dissipated in the resistance is a function of frequency. In general, the amount of feedback energy increases as the frequency to which the circuit is tuned increases. In this circuit, as the frequency increases, the reactance offered by Z_2 becomes smaller and consequently more current flows through Z_1Z_2 and the I^2R loss in the resistance of the network becomes greater. It is therefore obvious that sufficient energy may be dissipated in the network Z_1Z_2 to substantially overcome the effect of the feedback energy.

The operation of the tube under these conditions may best be explained by referring to the accompanying conventional gain characteristic curves shown in Fig. 2. Curve A is a characteristic curve illustrative of the relation of the amplification of a radio frequency stage to the tuned frequency of the receiving circuit. In this case it is assumed that the inductance of the plate circuit is so small that no oscillation will take place therefrom in the desired frequency range. Curve B is the same thing with a higher plate circuit inductance. The intersection of curve B with the curve C shows the frequency at which the particular amplifier will go into oscillation. Curve D represents the energy loss put into the system by the introduction of impedances Z_1 and Z_2 into the circuit. Curve E is a summation curve of B and D showing the net amplification that can be obtained when our invention is applied to the circuit having the same plate circuit inductance as used in obtaining curve B.

It will be seen from an inspection of curve E that the result of the introduction of the impedances Z_1 and Z_2 in Fig. 1 has been to substantially equalize the amplification over a wide frequency range. 115

By the proper choosing of these impedances, curve E can be made to take any position below the oscillation point. In other words, it can be made to cancel out all the feedback, only a part of it, or to cause an actual loss at all frequencies. 126

When only a part of the feedback energy is dissipated, the system is in a sensitive regenerative condition at all frequencies. 123

The value of the impedances of such networks can be calculated in accordance with the following mathematical deductions:

Referring again to the system shown in Fig.

Fig. 1, it may be assumed that when a voltage E is introduced into the inductance L_1 from an external source, whose frequency is that for which the circuit L_1, C_1 is resonant, the voltage applied to the grid of the tube may then be represented by the equation

$$e = I_1 \left(\frac{-j}{C_1 W} \right)$$

10 where $W = 2\pi X$ frequency and I_1 represents the current of the tuned circuit. The relation between the induced voltage of the tuned circuit and the resistance R of the circuit may be expressed by the equation $E = RI_1$.

15 Now if it is assumed that the plate circuit of the tube is so arranged that in-phase feedbacks occur from plate to the grid of the tube and through mutual inductance between L_2 and L_1 , then these feedbacks will produce, in effect, voltages in the tuned circuit $L_1 C_1$ which will add to the impressed voltage E and consequently result in an increase (I_2) in the current in the tuned circuit where I_2 is the additional component of current that 20 is caused to flow through this circuit because of the voltage induced into the circuit from the feedbacks.

25 If, therefore, the resultant voltage induced into the circuit through magnetic feedback be represented by E_m and the resulting voltage induced into the circuit by the electro-static feedback be represented by E_c , then the total induced voltage of the circuit may be represented by the conventional equation

$$E + E_m + E_c = R(I_1 + I_2).$$

30 The effect of the component I_2 is to produce a larger grid voltage and, hence, if the feedback voltages are sufficiently strong, oscillation will take place.

35 If we then introduce a resistance r into the tuned circuit, as has previously been done in the prior art, we can for any given frequency and for any given conditions of electro-static and electro-magnetic feedback, adjust this resistance to such a value for given circuit conditions that the total resultant current (I_3) flowing through the circuit $L_1 C_1$ will be reduced until $I_3 = I_1$. Hence the grid voltage in this case will be the same as the grid voltage without the effect of the electro-static and electro-magnetic feedback voltages thereby compensating for the effect of the electro-magnetic and electro-static feedbacks for the 40 particular given condition, but not for other conditions. For this given relation, the value of the resistance r necessary to effect this compensation may then be expressed by the equation,

$$r = \frac{E}{I_1} + \frac{E_m}{I_1} + \frac{E_c}{I_1} - R \quad (1)$$

45 when R is the resistance of the tuned circuit for the selected conditions.

50 It can be shown that both the electro-static

and the electro-magnetic feedback voltages are functions of the frequency for which the circuit $L_1 C_1$ is tuned. The value of r which will just cancel the feedback energy must therefore be changed as the resonant frequency is changed. Then r for each frequency absorbs an amount of energy

$$I_1^2 \times r$$

55 which is just equal to the increase in energy supplied to the tuned circuit by the electro-static and electro-magnetic feedback voltages. This does however, require manual adjustment of the resistance r for the cancellation of the energy feedback for different frequencies.

Obviously r can therefore be replaced by any energy absorbing system that will absorb an amount of energy equal to that absorbed by r as expressed in Equation (1).

60 This energy absorbing system need not be inside the tuned circuit. It might be a shunt circuit as illustrated in Fig. 1 or it might be a coupled circuit as shown in Fig. 3 and it may also be a series parallel network inserted in the tuned circuit as shown in Fig. 4, or these elements and functions might be incorporated within the tube itself.

65 In the circuit shown in Fig. 4 the current of the tuned circuit I_1 will divide between the two branches of the network in a proportion depending upon the relative magnitudes of the impedances Z_1 and Z_2 . If Z_1 includes a resistance and Z_2 is a complex impedance, Z_2 will vary with frequency. Therefore, the relative portions of the current passing through Z_1 and Z_2 will vary as the frequency is changed, thereby causing the current through the resistance to change. As the current through the resistance 70 changes, the energy used up in the resistance changes as a function of the frequency. Consequently, the network Z_1, Z_2 is an energy absorbing system which varies automatically with frequency and can by proper choosing 75 of its elements be made equivalent in energy absorption to the value of r derived in Equation (1).

80 In general this absorbing circuit may be associated with any portion of the system through which energy flows. It is thus not limited to the grid circuit and may be used in the plate circuit, with an auxiliary circuit coupled to the plate or the grid circuit, or in auto transformer connections associated 85 with either plate or grid circuit or may be incorporated inside the tube.

85 An interesting development of the circuit of Fig. 1 occurs when the grid and filament capacity is lumped with the impedance Z_2 . The circuit then becomes that of Fig. 5. Using this circuit, a particular broadcast amplifier was found to normally oscillate up to 450 meters before introducing the network $Z_1 Z_2$ into the circuit. When the net- 90

work shown in Fig. 5 was introduced, however, Z_1 being a resistance of about 100 ohms, and Z_2 being a condenser of about 50 micro-microfarads the amplifier was stable over the whole broadcast range without appreciable loss in efficiency above 450 meters.

The various figures of the accompanying drawings show different applications of the involved principles to tuned signal receiving circuits which applications are to be considered as illustrative only of our invention. Like numerals and letters in each case represent the same qualities of the apparatus, the particular values of the elements of the network being dependent upon the relations of the remainder of the circuit.

As previously explained, the energy absorbing network may also be inserted in the plate circuit.

20 Figs. 6, 7, 8 and 9 illustrate the respective plate circuits that are analogous to the respective grid circuit applications of the invention already described, namely Figs. 1, 3, 4 and 5.

25 It should be understood that the particular systems herein described and shown are merely for the purpose of illustrating and explaining our invention and are not intended as a complete exposition of all of the applications of the invention.

What we claim is:

1. The combination with a radio frequency amplifying system, of a circuit including an energy absorption network, energy absorbing means included in said network and means inversely responsive to frequency for bypassing portions of the reproducing current around said energy absorbing means and for causing other portions of said reproducing current, the latter being substantially proportional to the frequency of the system, to traverse said energy absorbing means whereby the absorption of energy by said network substantially equals the regenerative electro-magnetic and electro-static feedbacks in the system at substantially all frequencies within the normal operating range of the system.

2. The combination with a radio frequency amplifying system, of a circuit including an energy absorption network comprising a plurality of branches, energy absorbing means in one of said branches and means included in the network for bypassing predetermined portions of the reproducing current around said energy absorbing means and for causing other portions of said reproducing current to traverse said energy absorbing means, the portions of said current traversing said energy absorbing means being a predetermined function of the total regenerative electro-magnetic and electro-static feedbacks in the system at substantially all normal operating frequencies of the system whereby the frequency gain characteristic of the system

is controlled for all normal operating frequencies thereof.

3. In a radio frequency amplifying system, the combination with a conductor carrying the amplifying current, of an interposed energy dissipated network embodying a plurality of branches, energy absorption means included in one of said branches of said network and means included in other portions of said network for bypassing portions of the reproducing current around said energy absorption means, the bypassed current portions being inverse functions of the cumulative electro-magnetic and the electro-static feedbacks of the system whereby the current traversing the energy absorption branch of the network is modified in predetermined proportion to the main current and in accordance with the frequency of the system, thereby producing predetermined desired modifications of the frequency gain characteristic of the system.

4. The combination with a radio frequency amplifying system of a non-resonant network comprising a circuit containing a resistance element capable of dissipating electrical energy in the form of heat and a second circuit that controls the flow of current through the resistance element of the first named circuit, and that contains an element whose impedance is reactive at all frequencies within the range of the amplifying system, the resistance element of the first circuit being related to the reactance element of the second circuit so that the electrical energy dissipated in said resistance element in the form of heat is a function of the signal frequency which is being amplified.

5. The combination with a radio frequency amplifying system of a non-resonant network for preventing oscillation in a radio frequency amplifier, comprising a circuit containing a resistance element, and a second circuit containing an impedance of such a nature as to be reactive at all frequencies within the range of the amplifying system, whereby the flow of current through the resistance element of the first circuit is controlled, the amount of energy dissipated in the resistance element of the first circuit being a function of the frequency.

In testimony whereof we affix our signatures.
